HIGHEST NUMBER SHOWS BALANCE ON CHECK.

By

George B. Stillwagon
R. B. Woodward
his Attorney

UNITED STATES PATENT OFFICE.

GEORGE B. STILLWAGON, OF REDSTONE TOWNSHIP, FAYETTE COUNTY, PENNSYLVANIA.

COMMERCIAL INSTRUMENT.

1,389,849.

Specification of Letters Patent.

Patented Sept. 6, 1921.

Application filed November 6, 1919. Serial No. 336,106.

To all whom it may concern:

Be it known that I, GEORGE B. STILLWAGON, a citizen of the United States, residing at Redstone township, Fayette county, Pennsylvania, have invented certain new and useful Improvements in Commercial Instruments; and I do hereby declare the following to be a full, clear, and exact description of the invention, such as will enable others skilled in the art to which it appertains to make and use the same.

This invention relates to commercial instruments, and more particularly to what are generally known as company store checks, which may be sold for cash or issued in exchange for services rendered. Such checks are usually for a given amount or face value payable in merchandise, and those purchases which amount to less than the total value of the check may be deducted in some manner so as to clearly indicate the amount thereon still remaining to the credit of the owner of the check.

Heretofore such store checks have been arranged with spaces carrying figures in consecutive order from 1 to and including the number, in cents, that represents the total value of the check. Additional space is provided in the check for printing information about the check, such as the name of the company issuing it, the total value of the check, the date of issue, advertising, etc.

In the use of such checks, and starting with a check for the full amount, assuming that a purchase has been made that is smaller than the entire amount of the check, it has been the practice to deduct the amount of such purchase from the face value of the check either mentally or otherwise and then mark or punch a number which indicates the unused balance of the check. The amount of the next purchase paid for by the check is then deducted from the last punch mark mentally or otherwise, and the number corresponding to the new (and smaller) balance is then marked or punched, and so on until the full value of the check is exhausted.

When the check is merely marked or punched, practically the entire original check remains in the hands of the owner until the last cent has been punched or marked off, and then the check is turned in. In practice it has been discovered that these

checks are sometimes altered by obliterating the marks, filling in the punch marks, or patching portions of the check; and this has been so cleverly done that the fraud is not readily detected, especially in the hurried handling of such checks during the usual transaction of business. This so-called "doctoring" of these checks may be a source of considerable loss to stores which use them.

Accordingly the principal object of this invention is to provide a commercial instrument or company store check that shall overcome the above objections to those checks now in general use.

Another object of this invention is to provide an instrument of this character in which the balances may be quickly arrived at by the clerk with the least possible chance of mistake.

In carrying out this invention, a sheet is provided with a number of horizontal and vertical intersecting lines which form columns of spaces in which numbers are printed, ranging from 1 up to and including the number, in cents, that corresponds to the face value of the check. The highest number is arranged adjacent one edge of the sheet and the column which contains it extends along this edge so that as the successive amounts of the purchases are deducted, pieces of the check may be successively removed, leaving in the hands of the owner only that portion of the check which represents the balance. The columns of numbers of the check according to this invention are so arranged that the numbers at the adjacent ends of two adjacent columns are successive numbers, which enables the store clerk to tear off a single piece of the check with the numbers which are the equivalent of the amount of his purchase, even when such numbers run from one column to the next. In order to further facilitate the use of such checks, I have provided a check in which the numbers are separated into groups, which also prevents mistakes.

In the present invention, the numbers are divided into groups by contrasting horizontal and vertical lines, certain of these lines dividing the numbers in the columns into groups of 5, representing nickels and other lines dividing the numbers into hundreds representing dollars. In this way a clerk handling the check is able to locate much

more quickly and accurately the amount that represents the unused balance; and where the piece of the check is to be torn off, especially when purchases amount to a 5 dollar or more, the dollar division lines are a substantial aid in quickly finding the proper place to tear off the numbers equivalent to the amount of the purchase.

In conjunction with the improved check 10 I have provided an improved straight edge which renders it possible to quickly and accurately remove the proper portions of the check in one setting of the straight edge and thereby contributes to the general desirability of the instrument as a store check.

The foregoing and other objects and the novel features of the invention will be apparent from the following description taken in connection with the accompanying drawings in which—

Figure 1 is a face view of a check embodying the present invention.

Fig. 2 is a similar view, showing the straight edge in position for removing a 25 portion of the check corresponding to the amount of a purchase; and

Figs. 3 and 4 are partial face views of the check showing the straight edge in position to remove other portions of the check corresponding to the amounts of subsequent purchases.

While the instrument herein shown and described is particularly applicable to company store checks it will be understood that 35 the invention may be embodied in other instruments and that the size and shape and other features of the instrument may be varied to suit the particular purpose for which such instrument is to be used.

Referring to the drawing, 10 designates 40 the sheet of paper or other material constituting the body of the check and upon which are printed the lines, numbers, information, etc., according to this invention.

The check shown in Fig. 1 is substantially 45 full size, but its size and shape may of course be altered as desired. For the purposes of illustration a portion 11 at the right end of the check is provided with a space 50 to receive printing or writing, such as the name of the store issuing the check, the name of the owner, the date of issue of the check, and other information in connection with its use.

The space on the face of the check to the 55 left of the space 11 is divided into columns of spaces 12 by intersecting vertical lines 13 and horizontal lines 14. For convenience and for purposes of illustration these columns each contain 25 spaces and they are arranged vertically on the sheet 10. Furthermore, inasmuch as the denomination of the 60 check illustrated is \$3.00 there are necessarily twelve such columns of spaces. Of course, the columns may be arranged hori-

zontally and the number of spaces in a column and the number of columns may be varied as desired.

Numbers are printed in the columns of spaces, the last column, containing the lowest number 1, being located adjacent the space 11 and the numbers increasing toward the left until the left edge of the sheet is reached which contains the number corresponding to the face value of the check. 75 It will be seen that the numbers are so arranged that they run down one column, up the next, down the next and so on, which brings together successive numbers at the adjacent ends of two adjacent columns. 80 For example, numbers 25 and 26 are adjacent and successive, numbers 100 and 101 are adjacent and successive, numbers 275 and 276 are adjacent and successive, and so on. 85

It will be seen that every fifth horizontal line 141 is contrasted with the other horizontal lines in some suitable manner, as by making them considerably heavier or blacker than the lines between them. The 90 lines 141 extend across the columns of spaces and numbers dividing the numbers of each column into groups of 5, representing nickels or five-cent amounts. It is obvious that these horizontal contrasting lines may 95 be located at any other arbitrary division point, such as at every tenth line to divide the columns of numbers into groups of tens representing dimes or ten-cent amounts, for convenience in making calculations on the 100 instrument.

It is also desirable to provide lines or markings which shall divide the numbers into groups of say, one hundred, corresponding to dollars. For purposes of illustrating 105 this, I have provided contrasting vertical markings or lines 131, such lines 131 comprising every fourth line of the vertical lines 13, and being arranged parallel to the columns of numbers and contrasting with the other lines 13 by being heavier than or darker than these lines. The lines 131 divide the numbers into groups of one hundred, thereby expediting the calculations of deductions on the instrument. 110

I have provided a simple and convenient form of straight edge S for use in conjunction with checks embodying this invention. This straight edge is stamped or otherwise formed from a sheet of suitable material 120 such as sheet metal and comprises two longitudinal edges A and B, the former consisting of an edge 15 extending longitudinally of the device from the lower end, an edge 17 extending inwardly at right angles 125 to the edge 15 and toward the center line of the straight edge and an edge 18 extending longitudinally of the device at right angles to the edge 17. The other longitudinal edge B consists of a longitudinal edge 19 parallel 130

to the edge 15, an edge 20 opposite the edge 17 and extending outwardly at right angles to the edge 19 and an edge 21 parallel to the edge 18 and extending at right angles to the edge 20. Oppositely located inwardly and outwardly offset portions are thus provided at opposite points intermediate the ends of the straight edge.

Uses of the instrument are illustrated in Figs. 2, 3 and 4. Assuming that a check for full value has been presented for the deduction of the amount of a ten-cent purchase, the straight edge S is set as illustrated in Fig. 2, with the edge 20 above the number 290 and the corner of the check containing the numbers 291 to 300 inclusive torn off along the edges 19 and 20 of the straight edge S.

While it is not essential to this invention that the form of straight edge shown be used, or used as indicated, there is, however, a particular advantage in using the straight edge S and setting it in the manner indicated, because the clerk will then have the larger part of the sheet to take hold of in tearing off the part that is equivalent to the amount of the purchase, and the setting is such that the number representing the amount due is always uncovered and visible adjacent the edge that tears across the column. In those cases in which the amount to be deducted requires a tear across the sheet along one of the lines dividing the sheet into columns, any or all of the edges 15, 18, 19 and 21 may be of sufficient length to extend all the way across the sheet to provide a tearing edge without an offset portion.

Assuming that a twenty-five cent purchase is to be paid for out of the check after the equivalent of the ten-cent purchase has been deducted, the straight edge S is set as shown in Fig. 3, the edge 20 being set on the line below the number 265 and the edge 18 being set along the first vertical division line 13 to the right of the outer edge of the check, the edge 15 being positioned on the second division line 13. With the straight edge S so positioned, the numbers 266 to 290, corresponding to a twenty-five cent purchase, may be torn off in a single piece, inasmuch as the numbers in these two columns are all consecutive, and the numbers at the lower ends of these adjacent columns are successive. This is a substantial convenience when a large number of checks are to be handled.

In a similar manner the setting shown in Fig. 4 is arranged to remove a section of the check that corresponds to a purchase amounting to \$1.27, after the previous two purchases have been deducted. By a mental calculation the clerk may deduct the dollar and move over to the number 165, and then to complete the deduction of the twenty-seven cents it is only necessary to go back

in five steps of five numbers each to 140 and two additional units to a balance of \$1.38. The straight edge is then positioned to tear off at the line above the number 138 and on the vertical division lines on opposite sides of this number, leaving a balance of \$1.38 to the credit of the owner of the check.

It will be seen that in this improved check the amount of every purchase is torn off and the owner never has any part of the check that has been deducted and so he never has any material on hand with which to alter other checks. The highest number left on the check always indicates how much the check is still worth. It will be seen that in using the straight edge to tear off pieces of the check, it is not necessary to turn the same end for end, but by turning it about its longitudinal center line either off-set portion may be brought into tearing position.

While I have described my improved check in detail, it will be understood that some of the features thereof may be altered without departing from the spirit and scope of the invention.

What I claim is:

1. A store check comprising a sheet having thereon columns starting adjacent one edge with the highest number which corresponds to the value of the check, contrasting markings extending parallel to and across said columns and dividing the numbers thereof into multiples of a given value, the numbers at the adjacent ends of alternate pairs of adjacent columns being successive, whereby the amount of a purchase in any transaction within the total value of the check may be deducted from said check by removing in a single piece from the body of the sheet a portion carrying one or more of such numbers equivalent to the amount of such purchase.

2. A commercial instrument comprising a sheet having thereon columns of numbers starting adjacent one edge with the highest number which corresponds to the value of the instrument, the numbers at the adjacent ends of alternate pairs of adjacent columns being successive, whereby the amount of a purchase in any transaction within the total value of the instrument may be deducted from said instrument by removing in a single piece from the body of the sheet a portion carrying one or more of such numbers equivalent to the amount of such purchase.

3. A store check comprising a sheet having space for printing, writing, etc., upon a portion thereof, and upon another portion thereof intersecting horizontal and vertical lines dividing the same into columns of spaces, columns of numbers in said columns of spaces starting adjacent one end of the check with the highest number which corresponds to the face value of the check, certain of said lines horizontally and vertically

being heavier than and contrasting with the other of said intersecting lines to divide said numbers, respectively, into groups of five and one hundred, the numbers at adjacent ends of alternate pairs of adjacent columns being successive whereby the amount of the purchase of every transaction within the value of the check may be deducted therefrom by removing in a single piece

from the body of the sheet a portion carrying one or more of such numbers equivalent to the amount of such purchase.

In testimony whereof I hereunto affix my signature in the presence of two witnesses.

GEORGE B. STILLWAGON.
